(57) **CLAIM**

The ornamental design for a baby carriage, as shown and described.

DESCRIPTION

FIG. 1 is a top, front, right side perspective view of a baby carriage, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a right side view thereof, showing the baby carriage in an alternate configuration; and,

FIG. 9 is a right side view thereof, showing the baby carriage in a folded configuration.

The broken lines in the drawings depict portions of the baby carriage that form no part of the claimed design.
